(No Model.)

S. BURGESS.

CAR COUPLER.

No. 394,755.

Patented Dec. 18, 1888.

Samuel Burgess.
INVENTOR.

by *[Signature]*
Attorney.

UNITED STATES PATENT OFFICE.

SAMUEL BURGESS, OF VINCENNES, INDIANA, ASSIGNOR OF ONE-HALF TO
THORNTON WILLIAMS, OF OLIVET, MICHIGAN.

CAR-COUPLER.

SPECIFICATION forming part of Letters Patent No. 394,755, dated December 18, 1888.

Application filed September 13, 1888. Serial No. 285,298. (No model.)

To all whom it may concern:

Be it known that I, SAMUEL BURGESS, a citizen of the United States of America, residing at Vincennes, in the county of Knox and State 5 of Indiana, have invented certain new and useful Improvements in Car-Couplers; and I do hereby declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 My invention relates to improvements in car-couplers; and it consists in the novel construction and combination of the parts thereof, as will be more fully hereinafter described and claimed.

20 I have illustrated my improved coupler in the accompanying drawings, wherein like letters of reference are employed to designate similar parts in the several views, and in which—

25 Figure 1 is a perspective view of a part of a car with my improved coupler applied thereto, and Fig. 2 is a sectional elevation thereof.

A indicates the head, chambered and provided with coupling-pin holes and with a top 30 slot, a. The head A is formed on the outer end of draw-bar A², having a recess, A', in the top thereof.

On top of draw-head A², at each side of the recess A', journal-boxes C are attached, 35 in which a transverse rod or shaft, C', has bearing, and upon this shaft C' a disk, C², having a semicircular grooved periphery, is eccentrically mounted. The ends of said shaft C' have hand-wheels C⁴ fixed thereon, 40 and adjacent to the draw-bar a gear-wheel, C³, is also mounted on said shaft. The recess A' in draw-bar A² allows the disk C² to have free movement, as shown in Fig. 2.

To a lug or ear, b', on the rear part of the 45 draw-bar A², under the car, the rear end of a longitudinal bar, B, is attached, which passes through a slot, b², in the end of the car and up over the disk C², engaging with the semicircular groove thereof. The front end of 50 said rod B has an angle-iron, b, secured there-

to, through the horizontal member of which the pin P passes and is supported thereby; the head p of said pin resting on the top surface of the horizontal member of the said angle-iron. Attached to said rod B, in rear of the 55 head A, is a spring, S, which is secured at its lower end to the draw-bar.

In rear of the head A and to one edge of the bar A² an angularly-bent bracket-arm, E, is attached, having an upper rolled end to form 60 a bearing. Passing through said upper rolled end and a lug, e, formed with the adjacent side of the bar A², is a vertical shaft, E', which extends to the top of the car and has a hand-wheel, E³, fixed thereon. The said shaft E' is 65 also provided with a worm, E², at its lower end, which meshes with gear-wheel C³ on shaft C.

In operation, by turning one of the hand-wheels C⁴, situated at the side of the car, the 70 disk C² is raised, as shown in Fig. 1, raising the rod B and pin P. When said disk is over its dead-center, it is sustained as shown. After the link enters the head, the hand-wheel C⁴ is slightly revolved to turn the disk C² 75 slightly to one side of its dead-center, and the retractile effort of the spring S pulls said rod B down and forces the pin through the link and thereby couples. In operating the shaft C' by hand-wheel E³ on shaft E' from the top 80 of the car the worm E² revolves gear C³, when the motion is similar as when operating the coupler through hand-wheel C⁴. When the shaft C' is revolved, the gear C³ slightly raises the shaft E' through its connection with the 85 worm E², as will be readily understood by skilled mechanics.

My improved coupler embodies simplicity and effectiveness, and its use prevents injury and loss of life to train-men. 90

Having thus described my invention, what I claim as new, and desire to secure by Letters Patent, is—

1. In a car-coupler, the combination of the draw-bar having a recess therein and slot 95 or groove in the top surface of the head thereof, a longitudinal rod or bar extending over the top surface of the draw-bar and head and carrying the coupling-pin at its forward end, and a grooved disk eccentrically mounted on 100

a transverse shaft upon which the rod or bar has direct bearing and is actuated thereby to raise the coupling-pin, substantially as described.

5 2. In a car-coupler, the combination of the draw-bar having a recess therein and slot or groove in the top surface of the head thereof, a longitudinal rod or bar extending over the top surface of the draw-bar and head, having an angle-iron on the front end thereof for holding the coupling-pin, a grooved disk eccentrically mounted on a transverse operating-shaft with which said rod or bar is in direct engagement and is actuated thereby to 15 raise the coupling-pin, and a coiled spring attached to said bar or rod and to the draw-bar, substantially as described.

3. In a car-coupler, the combination of the draw-bar and head, the longitudinal rod attached at its rear end to said bar and carrying the coupling-pin at its front end, a transverse operating-shaft having an eccentrically-mounted disk-wheel thereon with which the rod engages, a gear-wheel, a spring attached 20 to said rod and draw-bar, and a vertical shaft having a worm thereon engaging the gear on 25

the transverse shaft, substantially as described.

4. In a car-coupler, the combination of the draw-bar A², provided with a recess, A', and 30 having head A, with a groove, a, a rod, B, attached at its rear end to a lug or ear, b', on the draw-bar and having an angle-iron, b, on its front end carrying the coupling-pin, the spring S, attached to said rod B, the transverse shaft C', having bearing in boxes C on the draw-bar, and a disk, C², with a grooved periphery, eccentrically mounted on said shaft, operated by hand-wheels, a gear, C³, on said shaft, a bracket-arm, E, and lug e, secured to 40 the draw-bar, and a vertical shaft, E', mounted in said arm E and lug e, having a worm thereon meshing with the gear C³ on shaft C', and a top operating hand-wheel, substantially as 45 described.

In testimony whereof I affix my signature in presence of two witnesses.

SAMUEL BURGESS.
